END SEAM FOR METAL CONTAINERS

Frank J. O'Brien, Pelham, N. Y., assignor to Continental Can Company, Inc., New York, N. Y., a corporation of New York

Application March 13, 1944, Serial No. 526,257

1 Claim. (Cl. 220—67)

The invention relates to new and useful improvements in metal containers and more particularly to the end seam for joining the closure end to the body portion of the container.

An object of the invention is to provide a double seam which is tight and which is constructed so as to provide a space disposed within the double seam and at the lower side thereof to facilitate the cutting of the closure end flange for releasing the end from the body.

A further object of the invention is to provide a double seam of the above type wherein the body wall flange is folded back and forth upon itself with the parts thereof so disposed that when the closure end flange is brought into tight sealing contact with the body wall flange and the folded back portions thereof a space will be formed at the outer lower side of the double seam which facilitates the cutting of the closure end flange so as to completely release the closure end from the body wall flange.

In the drawing which shows by way of illustration one embodiment of the invention

Figure 1 is a vertical sectional view through the opened portion of a container wherein the end is joined to the body wall by my improved double seam.

Figure 2 is an enlarged view showing the body wall flange preparatory to the folding of the same.

Figure 3 is a view similar to Figure 2 but showing the completed body wall flange before the closure end is assembled thereon.

Figure 4 is a view similar to Figure 3 showing the closure end placed on the flange of the can body preparatory to the forming of a double seam for joining the closure end to the container body.

Figure 5 is an enlarged view similar to Figure 4 but showing the completed double seam embodying the improvements.

Figure 6 is a view similar to Figure 5 but showing the seam cut for releasing the end from the body portion.

The invention is particularly designed for the joining of a closure end to the body wall of a metal container and has to do with the formation of a double seam which produces a hermetically tight connection between the closure end and the body wall and at the same time provides a double seam which can be severed outside of the body wall of the container for the releasing of the closure end from the body wall.

In the drawing, the container body is illustrated at 1 and the closure end which is secured

to one end thereof for sealing the same is indicated at 2. The double seam joining the closure end to the body wall is indicated at 3.

In carrying out the invention, the body wall

5 4 of the container body 1 is provided with an outwardly turned flange 5. This flange is of much greater width than the usual flange formed on a container body for the securing of an end closure thereto by double seaming. The flange 5 is folded back upon itself as indicated at 6 in Figure 3. This folded back portion is laid tightly against the underside of the main portion of the flange. The folded back portion is of less width than the remaining portion of the flange 10 15 so as to leave a space 7 into which the end of the closure end flange is tucked during the seaming operation. This folded back portion 6 is reversely folded upon itself as indicated at 8. This reversely folded portion is laid tightly 20 against the underside of the folded back portion 6 and is of sufficient length so that the end 9 thereof projects beyond the fold 10, formed when the flange is first folded back upon itself. This folding back of the flange brings the flange 25 with the folded back portions into substantially a plane which is at right angles to the body wall.

The end closure 2 is provided with the usual depression which is surrounded by a vertical wall 11 dimensioned so as to fit snugly within the 30 body of the container. The portion 12 of the closure end is referred to as the flange of the closure end. This flange extends outwardly and is curled downwardly and inwardly as indicated at 13. The inner surface of the flange is coated 35 with a sealing substance 14 of any usual type. This flange with the curled back portion 13 is so dimensioned that the closure end will fit within the container body and the flange of the container body will extend into the channel and the flange 40 of the closure end will rest thereon as shown in Figure 4. After the parts have been thus assembled, they are passed through the usual double seaming mechanism which includes a chuck 45 which is placed in the recess in the closure end and a series of seaming rolls that are brought into contact with the flange of the closure end and as the ends and rolls rotate relative to each other the closure end flange is rolled about the flange of the body wall and the end of the closure 50 end flange 13 is tucked into the space 7. Not only is the flange of the closure end caused to encircle the flange of the body wall and the folded back portions thereof, but the flange of the closure end is pressed against the flange and the folded 55 back parts forcing the folded back parts so that

they lie substantially parallel with the body wall and all the parts of the double seam are thus brought into tight hermetically sealed relation.

While the cover end flange tightly presses the folded back portions into contact, a space will be provided within the double seam by reason of the end 9 of the body wall flange projecting beyond the fold 10 in said flange. This space is indicated at 15 in the drawing.

It will be noted that in the completed double seam as shown in Figure 5, the folds in the body wall produce a structure wherein there are three thicknesses in the flange of the body wall between the outer wall 16 of the double seam and the inner end portion 13 thereof. This will place the space 15 well out from the body wall 1. When it is desired to sever the double seam, a cutter indicated in Figure 6 at 17 is brought into contact with the flange of the closure end in a line approximately directly below the space 15 and as the metal is severed it will be curled outward as indicated in this figure so as to release the closure end from the body wall. The end 9 of the inner folded part of the body flange supports the cover wall 16 against pressure of the blade 17.

By the improved construction, a tight seam can be formed for hermetically joining a closure end to the body wall of a metal container and at the same time said double seam is so constructed as to facilitate the cutting of the seam at the lower side thereof so as to completely re-

lease the end from the container body. Furthermore it will be noted that when the metal is cut at the lower side of the double seam which is outside of the wall of the container body there is no chance of any small particles of metal produced by the cutting action getting into the container when the closure end is raised.

It is obvious that minor changes in the details of construction and arrangement of the parts can be made without departing from the spirit of the invention as set forth in the appended claim.

I claim:

15 A double seam structure for joining a closure end to a container body comprising a body wall flange, said flange being folded back upon itself with the folded-back portion reversely folded so as to provide a three-wall thickness in the body flange with the walls thereof in tight contact and disposed substantially parallel with the wall 20 of the container body and a closure end flange rolled into tight encircling contact with the body wall flange and the folded-back portions thereof, the reversely folded-back portion of the body wall flange being slightly longer than the first-named folded-back portion and projecting below the fold therein so that the closure end flange will 25 be held spaced away from said fold in the body wall flange to facilitate the cutting of the closure end flange at the lower side of the double seam for releasing the end from the body.

FRANK J. O'BRIEN.
